UNITED STATES PATENT OFFICE.

JAMES S. FOX, OF JACKSON, MICHIGAN.

RAILWAY-RAIL.

1,010,886.

Specification of Letters Patent.

Patented Dec. 5, 1911.

Application filed May 9, 1911. Serial No. 625,998.

To all whom it may concern:

Be it known that I, JAMES S. FOX, a subject of the King of Great Britain, residing at Jackson, in the county of Jackson and State of Michigan, have invented new and useful Improvements in Railway-Rails, of which the following is a specification.

This invention relates to railway rails, the object of the invention being to provide a rail of this character which is constructed of sections and arranged so as to give additional strength to the rail and to provide means whereby the ball of the rail can be readily removed when worn and replaced by a new one at a minimum cost.

Another object of the invention is to provide a cushioning element between the rail sections, the said element being so arranged that it will hold the sections of the rail against moving relatively or creeping.

In the drawing, forming a portion of this specification and in which like numerals of reference indicate similar parts in the several views: Figure 1 is a side view of the rail. Fig. 2 is a vertical section therethrough on the line 2--2 of Fig. 1.

The rail comprises a ball member 1 and a base member 2, the former having an integral centrally located depending web 3 which fits in the space 4 defined by the standards or vertical portions 5 of the section 2. The underside of the ball 1 is provided at opposite sides of the web 3 with recesses 6 in which the upper ends of the spaced standards 5 are fitted, the walls 7 of the recesses 6 being spaced from the upper edges of the standards 5 for a purpose to be hereinafter described. The standards 5 of the member 2 are formed integral with a base flange 8 which may be attached in the usual well known manner to the ordinary rail supporting ties, (not shown). The surfaces 9 of the recesses 6 are disposed at the sides of the standards 5 to form guards by means of which any lateral thrust of the ball 1 may be transmitted to the standards 5 of the base section 2 of the rail.

The bottom of the web 3 is formed with a longitudinally extending retaining pocket 10, the walls of which being extended directly into the flat horizontal surfaces 11 on the bottom of the web. A cushioning element such as sand 12 is interposed between

the walls of the groove 10, the surfaces 11 and the wall 13 of the base member, the 55 said element permitting the ball 1 to yield under the weight of the rolling stock, the element 12 also forming a substantial continuous friction surface constituting retarding means to prevent longitudinal creeping of the ball. By providing the groove 10 in the bottom of the web 3 it presents a very broad contacting surface for the cushioning element 12, furthermore, the groove forms a retainer to hold the sand operatively confined against the bottom of the wall 13 of the base section 2.

From the construction described it will be seen that the usual grinding noises produced by the rolling stock's travel over the rail 70 will be taken up by the elastic element 12 and absorbed thereby. The construction not only eliminates such disagreeable noises but aids materially in preserving the respective sections of the rail. The construction is also 75 such that the sections can be more conveniently handled than a rail made from a solid piece of material and if desired, the use of fastening devices for connecting the sections of the rail with each other may be entirely 80 eliminated, the weight of the ball section and its connection with the base section being sufficient to hold the sections operatively associated with each other.

I claim:

A rail comprising a base section, standards extending upwardly from the base section and spaced to form an intervening recess, a ball member having recesses receiving the upper ends of the standards of the base 90 member, a web formed on the underside of the ball member and extending into the recess of the base member and provided at its bottom with a longitudinal groove and with flat faces adjacent to the groove, and 95 an elastic element interposed between the groove and flat faces respectively and the bottom wall of the recess in the base member.

In testimony whereof I affix my signature 100 in presence of two witnesses.

JAMES S. FOX.
